TENSION APPARATUS FOR LOOM WARP YARNS

Thomas J. Willis and William A. Smith,
Greenwood, S. C.

Application July 18, 1949, Serial No. 105,376

3 Claims. (Cl. 139—97)

1

This invention relates to looms and more especially to apparatus for relaxing the tension in warp yarns therein in order to prevent the occurrence of set marks in the woven fabric.

As is well known to those familiar with the art, ridges, commonly referred to as set marks, occur in woven fabric at the beat-up point of the lay of a loom whenever the loom is stopped and again started, whether the period between the starting and stopping of the loom be of short or long duration. Set marks are caused by sagging of the warp yarns between their points of suspension, that is, between the beat-up point of the lay and the whip roll at the rear of the loom, and this will invariably cause the woven fabric forwardly of the lay to tend to move rearwardly, as a result of which the last pick woven in the cloth, or the picks immediately following upon the loom again being started, will be compacted by the initial strokes of the lay, thus causing transverse ridges or set marks in the fabric, thereby resulting in an inferior product.

In order to prevent the occurrence of set marks in the cloth, it is a primary object of this invention to provide apparatus controlled by movement of the shipper handle of the loom for automatically releasing the tension on the warp yarns between their points of suspension immediately upon stopping the loom and for automatically again applying normal tension to the warp yarns immediately upon the loom again being started.

It is another object of this invention to provide means for preventing the occurrence of set marks in woven fabrics comprising a transverse pressure roll extending crosswise of the loom and being mounted on arms pivoted on the loom and having means connected to the pressure roll for automatically moving the same into engagement with the warp yarns of the loom between their points of suspension of the warp yarns upon the shipper handle of the loom being moved to an "on" position. Other means, automatically operable upon the shipper handle being moved to an "off" position are provided for moving the pressure roll out of engagement with the warp yarns, thus relaxing the pressure applied to the warp yarns by the pressure roll, as a result of which the normal tension of the warp yarns is considerably decreased and the warp yarns will not tend to pull the woven fabric rearwardly against the reed to cause the succeeding picks to be woven more closely together than is desired.

More specifically, it is an object of this inven-

2

tion to provide, in a loom having a whip roll shaft and a whip roll disposed rearwardly of the shaft, a pair of brackets extending upwardly from the whip roll shaft and having a second shaft oscillatably mounted therein, said second shaft having a pair of arms thereon in which the ends of a pressure roll are fixedly mounted. The pressure roll is preferably mounted between the whip roll and the whip roll shaft and has a connection between the same and the vertically movable plunger of a solenoid which is fastened to the loom. A switch is automatically closed upon the shipper handle being moved to an "on" position thus energizing the solenoid to cause the solenoid plunger to be drawn into the solenoid in such a manner as to cause the pressure roll to move into engagement with the warp yarns and to apply pressure to the same and to thereby place the warp yarns under tension. Immediately upon the shipper handle being moved to an "off" position, other means are provided to automatically release the solenoid plunger from the effects of the solenoid to thus allow the pressure roll to move out of engagement with the warp yarns, thereby relaxing the tension thereon.

Some of the objects of the invention having been stated, other objects will appear as the description proceeds when taken in connection with the accompanying drawings, in which

30 Figure 1 is a side elevation of a loom with parts broken away showing the invention as applied thereto and showing various parts schematically and in operating position;

35 Figure 2 is an enlarged elevation of the lower left-hand portion of the apparatus shown in Figure 1, the solenoid plunger being shown in a different position;

40 Figure 3 is a longitudinal vertical sectional view through the loom looking in the same direction as Figure 1 and also showing various parts of the loom schematically, but showing the pressure roll in non-tensioning position;

45 Figure 4 is an enlarged top plan view of the rear portion of the loom taken substantially along the line 4—4 in Figure 1 and showing the manner in which the tension applying pressure roll for the warp yarns is mounted adjacent the whip roll;

50 Figure 5 is an enlarged top plan view with the shipper lever in cross-section and is taken substantially along the line 5—5 in Figure 1 but showing only the end portion of the loom nearest the observer in Figure 1;

55 Figure 6 is an enlarged sectional plan view

taken substantially along the line 6—6 in Figure 1;

Figure 7 is an elevation of one side of one end of the loom taken substantially along the line 7—7 in Figure 1;

Figure 8 is a side elevation of a loom similar to Figure 1 but showing a modified form of the invention applied thereto, the parts at the front of the loom being shown in operating position while the parts of the invention at the rear of the loom are shown in inoperative position for purposes of illustration.

Referring more specifically to the drawings, the numerals 10 and 11 indicate the left-hand and right-hand side frame members, respectively, of a loom which rest on the floor. The side frame members 10 and 11 are connected at their upper ends by a conventional arch connection 12 suitably secured to the respective side frame members, about half way between the front and rear ends of the loom frame. The upper ends of the loom side frame members 10 and 11 are connected near the front end of the loom by a conventional breast beam 13 suitably bolted to the loom side frame members 10 and 11. Near their lower ends, the loom side frame members 10 and 11 are connected by a front girt 14 and a rear girt 15 suitably secured to the loom side frame members 10 and 11.

A conventional shaft 16 is oscillatably mounted at its ends in the loom side frame members 10 and 11 and has the lower ends of swords 17 and 20 fixedly mounted thereon, the upper ends of which support a conventional horizontally disposed lay 21 and a reed cap 22 which are secured to the swords 17 and 20 in a conventional manner and between which a conventional reed 23 is disposed. The front ends of pitman rods 25 and 26 are pivotally connected to the swords 17 and 20, respectively, as at 28 and 29, their rear ends being oscillatably mounted on crank throws of a crank shaft 30. The crank shaft 30 is driven in a conventional manner and is mounted in bearing blocks 31 and 32 suitably secured to the side frame members 10 and 11.

Bolted to the proximate surfaces of the loom side frame members 10 and 11 adjacent the upper rear ends thereof are whip roll shaft bearing brackets 34 and 35 in which a conventional whip roll shaft 36 is oscillatably mounted. The whip roll shaft 36 has conventional whip roll arms 37 and 40 fixedly mounted thereon and which extend rearwardly and upwardly at a slight angle relative to the horizontal and have the remote ends of whip roll pivot arms or brackets 41 and 42, respectively, oscillatably mounted therein. These whip roll pivot brackets 41 and 42 extend forwardly and have opposite ends of a conventional vibrating whip roll 43 mounted therein.

In Figures 1 and 3, warp yarns 45 are drawn upwardly from a conventional warp beam 46, which is shown schematically, and which has conventional tension means associated therewith, not shown. The warp yarns 45 pass over the vibrating whip roll 43 and then extend horizontally above the whip roll shaft 36. The warp yarns 45 are usually divided into two sheets 45a and 45b by conventional lease bars 47 and 49 and these sheets of warp yarns 45a and 45b pass through conventional harnesses 51 and 52, respectively, to which vertical reciprocation is transmitted, by conventional means, not shown, when the loom is in operation.

The sheets of warp yarns 45a and 45b then pass through the conventional reed 23 and are woven into fabric F. The fabric F is then taken up by a conventional sand roll 55 around which the fabric passes and then passes over a take-up guide roll 56. The cloth then extends downwardly and is finally wound about a conventional cloth take-up roll 57, the rolls 55, 56 and 57 being rotatably mounted in a conventional manner in the side frame members 10 and 11.

The loom also has a conventional shipper lever 60 oscillatably mounted, as at 61 (Figure 7), on a bracket 62 suitably secured to the loom side frame member 10. The shipper lever 61 extends upwardly and through a conventional shipper lock bracket 63 projecting outwardly from the loom side frame member 10. The shipper lock bracket 63 has a slot 64 therein which is penetrated by the shipper lever 60 and the bracket 63 is also provided with a locking notch 65 at its upper end in Figure 5 which is provided for holding the shipper lever 60 in an operating position. The upper end of the shipper lever 60 has a shipper handle 66 integral therewith. When the shipper handle 66 is in operating position, as shown in Figure 7, the upper portion of the shipper lever 60 engages an outwardly turned leg 67 of a conventional dagger lever 70.

The dagger lever 70 is oscillatably mounted intermediate its ends as at 72 and has oscillatably connected thereto, below its pivot point, a dagger 73 which extends rearwardly in Figures 1 and 8 and, when in the raised position shown in Figure 1, this dagger 73 is adapted to be engaged by a bunter 74 depending from the lay 21 for moving the shipper lever 60 out of the notch 65 to stop the loom. Intermediate the ends of the dagger 73, the upper end of a connecting rod 75 is pivotally connected, and this rod 75 is actuated by conventional stop motion means, not shown, for moving the dagger 73 from a lowered position to the raised position shown in Figure 1 so as to be engaged by the bunter 74 upon a beat-up stroke of the lay 21 to thus cause the pivoted dagger 73 to move in a counterclockwise direction in Figure 1 and to move the shipper lever 60 out of the notch 65 in the shipper lock bracket 63. A conventional tension spring 71 is connected to the lower end of the shipper lever 60 in Figure 7 which will normally urge the shipper lever 60 in a counterclockwise direction in Figure 7 to thus stop the loom in a conventional manner.

The parts heretofore described are conventional parts of a loom, and it is with these parts that this invention is adapted to be associated.

The lower ends of upstanding bearing blocks 80 and 81 (Figures 1, 3 and 4) are fixedly mounted on the conventional whip roll shaft 36 and have oscillatably mounted in the upper ends thereof a transverse operating shaft 82. The shaft 82 has the lower front ends of pressure roll arms 83 and 84 fixedly mounted therein which extend upwardly and rearwardly at a slight angle in Figure 3 and have opposed ends of a transverse pressure roll 85 fixedly secured therein as by set screws 86. When the loom is in operation, the pressure roll normally rests in engagement with and is supported by the upper surfaces of the warp yarns 45 as shown in dotted lines in Figure 3 and, upon starting the loom, the pressure roll is moved from the dotted line to the solid line position shown in Figure 3 by means to be presently described.

It will be noted in Figure 4 that the upper end 75 of the shaft 82 terminates in a vertical plane

slightly inwardly of the whip roll arm 40 while the lower end thereof extends outwardly above and beyond the loom side frame member 10 and has the front end of an arm 90 fixedly and adjustably mounted thereon as by a set screw 91 (Figures 1 and 4). This arm 90 extends rearwardly and has a plurality of spaced bores 92 therein in any one of which the upper end of a cable 93 is adapted to be inserted according to the desired amount of tension to be effected in the warp yarns 45 by the pressure roll 85, for securing the upper end of the cable 93 to the arm 90. The lower end of the cable 93 is connected, as by tying, to an eye portion 94 of a vertically disposed solenoid plunger 95. The solenoid plunger 95 is mounted for vertical sliding movement in a housing 96 having a suitable solenoid coil 97 therein which, when energized in a manner to be later described, causes the solenoid plunger 95 to move downwardly in Figures 1 and 2.

The solenoid coil housing 96 is secured by a strap iron member 100 to an angle plate 101 as by screws 103. The plate 101 is secured as by screws 104 to the outer surface of the loom side frame member 10. One of the screws 104 also penetrates the right-hand portion of the strap iron member 100 in Figure 2 and assists in securing the strap iron member 100 to the angle plate 101.

The right-hand flange of the strap iron member 100 in Figures 1, 2, 4 and 6 extends forwardly and is then bent outwardly as at 105 and then bent forwardly again as at 106. The angle plate 101 has an outwardly projecting front end portion 107, the front end of which is bent rearwardly as at 108 and coincides with the forwardly bent portion 106 of the strap iron member 100.

The portions 105 and 106 of the strap iron member 100 and the portions 107 and 108 of the angle plate 101 form a housing in which an insulation plate 111 has vertical sliding movement. This insulation plate is suitably secured, as by an adhesive material, to the lower surface of a contact bar 112 in Figure 2 which normally engages contacts 113 and 114 secured to but insulated from the vertical leg of the angle plate 101. The contact bar 112 also has a centrally disposed upwardly projecting portion 116 integral therewith which has an insulation member 117 adhesively secured to the upper end thereof and which is adapted to be engaged by the lower end of a pin 120 extending downwardly from an arm 121. The arm 121 has a disk-shaped portion 122 integral therewith (Figure 6) which is suitably secured to the solenoid plunger 95 so that vertical movement of the solenoid plunger 95 will cause like movement to be transmitted to the disk and the pin 120. A compression spring 124 is mounted between the horizontal leg of the angle plate 101 and the lower surface of the insulation plate 111 in Figure 2 and normally urges the contact bar 112 into engagement with the contact members 113 and 114 to complete a circuit therebetween.

The housing 96 for the solenoid coil 97 has a vertically extending slot 96a therein which is loosely penetrated by the arm 121 so as to permit vertical movement of the arm 121 and its pin 120 relative to the housing 96. The contact members 113 and 114 have the ends of electric wires 126 and 127, respectively, secured thereto, and the wire 126 extends to one side of the solenoid coil 97 and the solenoid coil 97 also has a wire 130 extending therefrom. The electric wire 127 extends to one side of a sensitive switch 133 (Fig-

ures 5 and 7) secured as by screws 134 to an arm 135 projecting from the outer surface of the vertical side frame member 10 of the loom. The wire 130 extends to one side of a male plug 131 and another wire 132 extends from the other side of the plug 131 to the other side of the switch 133.

The switch 133 has a lever 136 extending upwardly therefrom to which one end of a tension spring 137 is connected, the other end of the tension spring being connected to the lower end of the shipper lever 60 in Figure 7.

The lever 136 of the switch 133 is shown in a closed position in Figure 7 since the shipper handle 56 is shown in an operating position, and, upon the switch 133 being closed, current will flow from the plug 131 which is adapted to be plugged into a suitable source of electrical energy, not shown, through wire 132 to the switch 133 and then through the wire 121 to the contact 114 in Figures 1 and 2. Since the compression spring 124 has urged the contact bar 112 into engagement with the contacts 113 and 114, the current will then flow through the contact bar 112 and the contact member 113, through the wire 126, to one side of the solenoid coil 97. Current will then flow from the other side of the solenoid coil 97 through the electric wire 130 to the other side of the plug 131, thus completing a circuit to the solenoid coil 97.

Now, upon the solenoid coil 97 being energized, the solenoid plunger 95 will be pulled downwardly and this solenoid plunger 95 has an annular groove 140 therein which will be engaged by the left-hand end of a spring-loaded arm 142 in Figure 2 to thus lock the solenoid plunger 95 in a lowered position. The spring-loaded arm 142 is mounted for horizontal sliding movement in a tubular member 143, secured as by welding to the upper end of the housing 96 in Figure 2. The arm 142 has an upwardly projecting spring anchor portion 145 integral therewith to which one end of a tension spring 146 is connected, the other end of the tension spring 146 being connected to a suitable spring anchor 147 projecting from the vertical side frame member 10.

When the solenoid plunger 95 is pulled downwardly in the manner heretofore described, this will, of course, cause the arm 90 to move downwardly at its left-hand end in Figure 1 which will, in turn, move the pressure roll 85 from the dotted line position to the solid line position shown in Figure 1 and will thereby increase the tension in the warp yarns 45 and will maintain this tension in the warp yarns until the spring loaded arm 142 is moved out of engagement with the annular groove 140 in the solenoid plunger 95, by means to be later described.

When the solenoid plunger 95 is pulled downwardly in the manner heretofore described, this will also cause the pin 120 on the arm 121 to be moved into engagement with the insulation pad 117 on the upper end of the projection 116 of the contact bar 112 and will thus move the contact bar 112 out of engagement with the contact members 113 and 114, which will break the circuit to the solenoid coil 97 to thus prevent its being overheated during the time the loom is in operation and it is thus seen why it is necessary to lock the solenoid plunger 95 in a lowered position, inasmuch as the tension in the warp yarns 45 is sufficient to raise the pressure roll 85 in Figure 1 upon the solenoid plunger 95 being released from the spring pressed arm 142 in the manner to be presently described.

The arm 142 has an eye portion 150 at its right-hand end in Figures 1 and 2 to which a cable or cord 151 is suitably connected. This cable 151 extends forwardly and is suitably connected, as at 152, to the lower end of a lever arm 153. The lever arm 153 is oscillatably mounted as at 154 on the vertical side frame member 10 and then extends upwardly and has a cam portion 155 integral therewith (Figure 5). The angular cam face of this cam portion 155 is slidably engaged by a mating cam faced portion 157 of a horizontally disposed lever arm 160 which is oscillatable on a vertical axis on a bolt 161. The bolt 161 is secured in one end of a bracket 162 which is secured as by screws 164 to the loom side frame member 10.

A tension spring 167 normally urges the lever arm 153 in a clockwise direction in Figure 1 and urges the face of the cam portion 155 against the cam face 157 of the horizontally disposed lever arm 160. The horizontally disposed lever arm 160 extends to the right in Figures 1 and 5 beyond its pivot point 161 and is adapted to be engaged by the outer surface of the shipper lever 66 (Figure 7) upon the shipper handle 66 being moved from operative to inoperative position.

Now, upon the shipper handle being moved to an "off" or inoperative position, the lever arm 160 is caused to move in a clockwise direction in Figure 5 and the cam surface 157 thereof will then slide against the cam surface 155 and will cause the vertically disposed lever arm 153 to move in a counterclockwise direction in Figure 1 so as to pull the spring-loaded arm 142 out of engagement with the groove 140 in the vertically disposed solenoid plunger 95. This will, of course, release the solenoid plunger 95 and will permit the warp yarns 45 to raise the pressure roll 85, thus relieving the tension on the warp yarn.

It is thus seen that upon starting the loom, the pressure roll 85 is moved downwardly to increase the tension on the warp yarns 45 and, upon stopping the loom, the shipper handle 66 moves in a counterclockwise direction in Figure 7 thus opening the switch 133 to prevent the solenoid coil 97 from being energized upon the solenoid plunger 95 being released and also resulting in the tension in the warp yarns being decreased immediately upon stopping the loom.

Now, since set marks in the fabric are usually caused by the normal tension applied to the warp yarns tending to pull the fabric F slightly toward the rear of the loom, it is thus seen that by relieving the tension on the warp yarns when the loom is not operating, the occurrence of set marks in the fabric is prevented.

Referring to Figure 8 there is shown a modified form of the invention which is identical to the original form shown, with the exception that the pressure roll 85 extends beneath the warp yarns instead of over the warp yarns as in the original form of the invention shown in Figures 1, 3 and 4, and this pressure roll is raised instead of lowered for increasing the tension on the warp yarns 45. Therefore, like parts will bear the same reference characters in both forms of the invention with the exception of the modified parts in Figure 8 which comprise a lever arm 170 fixedly mounted on the end of the shaft 82 nearest the observer in Figure 8 and which is identical to the arm 90 in the original form of the invention. However, this arm 170 extends forwardly instead of rearwardly and also has a plurality of bores 171 therein in any one of which the upper end of a cable 93 may be suitably

secured. It is manifest that the greater the distance between the point at which the cable 93 is connected to the arm 170, the smaller will be the distance the pressure roll 85 is moved upwardly by the solenoid plunger 95, and the tension effected in the warp yarns 45 will be lessened accordingly.

It is thus seen that with the modified form of the invention shown in Figure 8, upon starting the loom, the solenoid coil 97 will be energized in the same manner as that described for the original form of the invention, thus causing the cable 93 to move downwardly and this will, in turn, cause the lever arm 170 to partially rotate in a clockwise direction in Figure 8.

This, of course, will cause the pressure roll 85 to move from the solid line to the dotted line position shown in Figure 8, thus engaging the lower surfaces of the strands of warp yarns 45 and forcing them upwardly to thereby increase the tension to the desired amount on the warp yarns. Now, upon moving the shipper handle 66 from an "on" to an "off" position the solenoid plunger 95 will be relaxed in the manner heretofore stated for the original form of the invention thus allowing the arm 170 to move from the dotted line to the solid line position shown in Figure 8 due to the weight of the pressure roll 85, which will result in the pressure roll 85 moving downwardly and out of engagement with the lower surfaces of the warp yarns 45 thus releasing tension on the warp yarns so they may be in a relaxed condition during the time that the loom is not in operation.

It is to be noted that the cable 151 will be relaxed sufficiently, as shown in Figure 8, when the shipper handle is moved to operating position and the solenoid plunger 95 is in elevated position, to thus permit the spring-loaded arm 142 to move into the annular groove 140 in the solenoid plunger 95 immediately upon the shipper handle 66 being moved to operating position and the circuit being completed to the solenoid coil 97 in the manner heretofore described.

Although the solenoid 97 reacts immediately to the moving of the shipper handle from inoperative to operative position, the parts are shown in Figure 8 with the shipper handle in operating position and the solenoid plunger 95 in inoperative position so as to illustrate the slackened condition of the cable 151 as the loom is being started.

In the drawings and specification there has been set forth a preferred embodiment of the invention, and although specific terms are employed, they are used in a generic and descriptive sense only, and not for purposes of limitation, the scope of the invention being defined in the claims.

We claim:

1. In a loom having a lay and cloth take-up means adjacent the lay and also having a whip roll and a warp beam and warp yarns directed from the warp beam over the whip roll and to the lay for weaving the same into cloth, said loom also having a shipper handle thereon, an eccentrically mounted pressure roll extending transversely of the loom and being oscillatable on the axis of its eccentric mounting, a lever arm connected to the eccentric mounting at its axis, a solenoid coil carried by the loom and disposed below the lever arm, a solenoid plunger in the solenoid coil, a connection between the solenoid plunger and the lever arm, means electrically and automatically operable upon mov-

ing the shipper handle to an operative position for automatically energizing the solenoid coil to thus cause the plunger to be drawn into the same and to move said pressure roll relative to the warp yarns to increase the tension thereon, and means automatically operable upon moving the shipper handle to an inoperative position for releasing the solenoid plunger to permit the pressure roll to move away from a pressure applying position relative to the warp yarns.

2. In a loom having a lay and a cloth take up means adjacent the lay and also having a whip roll and a warp beam and warp yarns directed from the warp beam over the whip roll and to the lay for weaving the same into cloth and said loom also having a shipper handle thereon for stopping and starting the lay, an eccentrically mounted pressure roll extending transversely of the loom and being oscillatable on the axis of its eccentric mounting, a lever arm secured to the eccentric mounting at its axis, said pressure roll normally resting upon the warp yarns when the shipper handle is in an inoperative position, electrically operable means responsive to movement of the shipper handle to operative position for moving the pressure roll under pressure against the warp yarns to create tension therein comprising a solenoid coil carried by the loom and disposed below the lever arm, a vertically movable solenoid plunger in the solenoid coil, a source of electrical energy, a connection between the solenoid plunger and the lever arm, electric switch means associated with the shipper handle, electrical connections between the source of electrical energy and the switch means and the solenoid coil, said switch means being closed upon moving the shipper handle to operative position for energizing the coil to cause the plunger to move the pressure roll against the warp yarns to increase the tension thereon, a normally closed relay switch interposed in the electrical connections between the first-named switch and the solenoid coil, spring loaded locking means disposed adjacent the plunger and means on said plunger engageable by the spring loaded locking means upon the plunger being moved into said solenoid coil for locking the pressure roll in a pressure applying position, means associated with the solenoid plunger for engaging said relay switch to open the same

upon said locking means being operative upon the solenoid plunger and means engageable by the shipper handle upon moving the same to inoperative position for moving the spring loaded locking means out of engagement with the plunger to release the same and permitting the pressure roll to relax its pressure against the warp yarns.

3. In a structure according to claim 2, said means engageable by the shipper handle for moving the spring loaded locking means out of engagement with the solenoid plunger comprising a first lever pivoted intermediate its ends on the loom and about a vertical axis, a second lever disposed adjacent the first lever and pivoted intermediate its ends on the loom about a horizontal axis, a cable connecting one end of the second lever to one end of the spring loaded locking means, cam means on the proximate ends of said levers, spring means normally urging the cam means on the second lever into engagement with the cam means on the first lever and also urging the end of the second lever remote from the cam means toward the spring loaded locking means, the end of the first lever remote from said cam means being disposed in the path of movement of the shipper handle as it is moved to inoperative position to be engaged thereby and to impart movement to the first lever to thereby cause said second lever to pivot about its axis in the opposite direction from which it is normally urged to, in turn, cause the spring loaded locking means to move out of engagement with the solenoid plunger.
